UNITED STATES PATENT OFFICE.

ISAAC G. STRAUSS, OF MILWAUKEE, WISCONSIN.

KNITTED CAP.

Application filed April 24, 1922. Serial No. 556,290.

To all whom it may concern:

Be it known that I, ISAAC G. STRAUSS, a citizen of the United States, and resident of Milwaukee, in the county of Milwaukee and State of Wisconsin, have invented new and useful Improvements in Knitted Caps, of which the following is a description, reference being had to the accompanying drawings, which are a part of this specification.

10 This invention relates to improvements in knitted caps and particularly to caps of this type which are provided with a flap designed to protect the ears and neck of the wearer.

15 Specifically the invention consists in a knitted cap so formed as to provide a band portion around the lower edge of the cap, one section of this band portion being foldable to a position where it acts as a protection for the ears and neck of the wearer, this section of the band, in its inoperative position being secured in a position folded against the body of the cap so as to complete the appearance of the complete band 25 around the bottom of the cap.

The invention also consists in the novel construction and manner of forming the cap as will be made more apparent in the accompanying specification and drawings.

30 In the drawings:

Fig. 1 is a side elevation of the cap,

Fig. 2 is a top plan view of the same,

Fig. 3 is a front elevation of the cap, and,

Fig. 4 is a view of the cap with the protecting flap extended.

Referring now more particularly to the drawings it will be seen that the cap comprises two body sections 10 and 11 of tubular construction, joined together by a seam 40 12 which extends transversely of the cap, instead of from front to rear as is usual in caps of the ordinary construction. The front portion 11 of the cap is formed with a band 13 which band is formed by folding 45 a portion of the body backwardly upon itself as clearly shown in Fig. 4. The rear portion of the cap 10 is provided with an adjustable band 14 also formed integrally with the body portion 10 and adapted in 50 one position to be folded up upon the body portion 10 and secured in place by buttons 15 carried by the band portion of the other cap section.

Secured to the inner side of the band 14 55 is a flap 16 secured to the band 14 by stitching 17. The other end is attached to the

flap by a button and button-hole connection 18. When the adjustable band 14 is in its extended position it acts as a protection for the ears and neck of the wearer and in 60 order to hold this band in this position the flap 16 is unbuttoned and passed around the neck of the wearer and again buttoned to the button 18' at the opposite end of the band. This securely holds the band portion 14 against the ears and neck of the wearer and provides protection from the elements. 65

In knitting the cap a portion thereof is knitted with what is called a "cuff stitch" 70 thereby forming a circumferential, relatively thinner portion 19. The edges of the bands 13 and 14 are also knitted with the cuff stitch, these sections being indicated by the reference character 75 20. By forming the circumferential band of a relatively thinner portion the folding of the adjustable band 14 is facilitated. Also these lines of cuff stitching provide a form fitting construction which will readily 80 give and at the same time closely fit the head of the wearer. The balance of the cap is preferably formed in what is called the "French rack stitch." Furthermore, the inside of the cap is brushed to form a 85 woolly inner surface. From the foregoing it will be obvious that in accordance with this present invention there is provided a cap capable of being worn in the ordinary manner or with the adjustable band 14 extended so as to take the place of ear muffs and muffler. It will be furthermore obvious that the construction of the cap is such that when the adjustable band is folded up against the body portion of the cap that the 90 cap will have an ornate and stylish appearance. 95

While the specific arrangement herein described and illustrated has been found to be desirable in every respect, this invention is not necessarily limited to this specific arrangement of parts and the manner of manufacturing, but reservation is made to make such changes and modifications as may come within the purview of the accompanying claims. 105

Claims—

1. A head covering comprising a body portion formed of front and rear sections sewed together by a transverse seam, each section being provided with an integral band portion, one of said band portions 110

being fixed and the other being adjustable to an extended position for covering the ears and neck of the wearer, and means for securing said adjustable band portion in its 5 extended position.

2. A knitted cap of the class described comprising front and rear sections secured together by a seam extending transversely of the cap, each cap section being provided 10 with a band portion normally folded against said body portion, one of said band portions being fixed and the other being adjustable to an extended position for protecting the neck and ears of the wearer, 15 means for holding said adjustable band portion in its folded position, and a flap permanently connected at one end to one end portion of the band and detachably connectable at its other end to the opposite end of said 20 band.

3. In a knitted cap of the class described, a body formed of front and rear sections joined together by a seam extending transversely of the cap, a band portion extending 25 around the lower edge of said cap, said band portion being formed in sections, one of said band sections being fixed and the other of said sections being unfoldable to

an extended position, means for securing said foldable band section in its upper position, and an independent flap carried by said foldable band section and adapted to encircle the neck of the wearer to hold said band portion in engagement with the ears and neck of the wearer. 30 35

4. In a cap, two knitted body sections joined together by a seam extending transversely of the cap, integral knitted band portions connected with said body sections by a section of knitting, forming a relatively 40 thinner portion, one of said band portions being adjustable to an extended position for protecting the ears and neck of the wearer, means approximately in alignment with the transverse seam for securing this 45 adjustable band section in its upper position, and an independent flap of less width than the band carried on the inside of said band section an adapted to pass around the neck of the wearer and to be connected to 50 the opposite end of the band for holding said band section against the ears and neck of the wearer.

In testimony whereof, I affix my signature:

ISAAC G. STRAUSS
